ADDING ATTACHMENT FOR TYPEWRITING MACHINES

Original Filed June 10, 1926

Inventor:
G. O. Degener;
by his Attorneys:

Pearson & Wright -

UNITED STATES PATENT OFFICE

GUSTAVE O. DEGENER, OF SAN FRANCISCO, CALIFORNIA, ASSIGNOR TO ROYAL TYPE-WRITER COMPANY, INC., OF NEW YORK, N. Y., A CORPORATION OF NEW YORK

ADDING ATTACHMENT FOR TYPEWRITING MACHINES

Original application filed June 10, 1926, Serial No. 114,950. Divided and this application filed May 25, 1927. Serial No. 194,134.

This application is a division of my prior application Serial No. 114,950 filed June 10, 1926 (now Patent No. 1,688,805, granted Oct. 23, 1928).

10 The object of this invention is to provide means located adjacent the keyboard of the typewriting machine for operating the add and subtract lever of computing mechanism which is constructed as an attachment to the typewriting machine and is placed at one side thereof. This obviates the necessity of removing the hand from the keyboard of the typewriter in order to operate the add and subtract lever.

15 The invention is applicable to computing mechanisms of widely different types and the computing mechanism itself is not disclosed in detail. It may be of the same general character as that shown in my prior application Serial No. 736,896 filed Sept. 10, 1924 (now Patent No. 1,633,242, granted June 21, 1927).

20 The invention is disclosed as embodied in a construction wherein the return movement of the typewriter carriage after it has been positioned for computing in the grand totalizer automatically returns the add and subtract lever to add position if it has previously been set to subtract. It is obvious, however, 25 that the invention is applicable to other types of mechanism.

In the drawings:

25 Figure 1 is a top plan view of the attachment in position upon a typewriting machine conventionally illustrated.

30 Figure 2 is a detached view showing the train of connections from the add and subtract lever at the left hand side of the keyboard to the add and subtract lever of the totalizer and the carriage operated means for returning the same to add position.

35 The invention has been illustrated in connection with a Royal standard machine although it is capable of application to any of the various commercial typewriters. The typewriting machine itself has, therefore, been illustrated only conventionally and there is shown a machine frame A, a platen C which is carried by the usual travelling carriage, 40 type bar mechanism D, ribbon mechanism E

and a keyboard F provided with numeral keys G having levers H. These parts are or may be of any desired construction.

45 The adding mechanism is enclosed in a casing I at the right hand side of the typewriting machine and contains computing mechanism which may be set to add or subtract by the movement of a short lever 82 to one or the other of two positions. This lever is connected by a short link 83 to an up-standing arm 84 of a three armed lever which is pivoted at 85 to an appropriate support. One arm 86 of this lever is connected by a link 87 to an arm 88 extending rearwardly from one end of a rock shaft 89, which underlies the keyboard of the typewriting machine. The other end of this rock shaft has an arm 90 connected by an upstanding link 91 to an arm 92 of a bell crank lever pivoted at 93, the other arm of which lever is bent to form a finger piece and indicator 94 which coacts with an indicating device 95 on a bracket 96 secured to the side frame of the machine. A movement of the finger piece 94 from one position to the other will, therefore, shift the mechanism as 55 desired for addition or subtraction.

50 The other arm 97 of the three armed lever is connected by a spring 98 which engages a plunger 99 with one arm 100 of a bell crank lever which is pivoted at 101 to an appropriate support and has an upwardly and rearwardly extending arm 102 terminating in an offset 103. A shaft 104 at the rear of the computing mechanism carries a cam member 105 which is actuated by a pin 106 on the carriage and clearly set forth in my Patent No. 1,624,318 of April 12, 1927. When this shaft is rotated on the return movement of the carriage a cam 107 mounted thereon will engage the offset 103 and actuate the lever 102 thereby through the intermediate connections, returning the lever to add position if it has been previously shifted to the subtract position. This assures that the mechanism shall be in the add position when the 60 next item is written in the column totalizer unless it is especially desired to move the same to subtract position for the purpose of entering a credit item. If it is desired to enter a credit item, the operator can shift 65

the lever to subtract without removing her hand from the keyboard.

It will be obvious that the precise embodiment of the invention may be varied in accordance with the type of mechanism to which it is applied and that other detail changes may be made without departing from the spirit of the invention which is to be regarded as limited only by the scope of the appended claims.

10. I claim as my invention:

1. In a combined typewriting and computing machine, the combination of an adding and subtracting computing device, a movable carriage for the typewriter, manual means to cause the computing device to add or subtract, and means actuated by a shifting of the carriage to actuate the manual means to restore the computing device to adding condition when during the preceding operation it shall have been caused to subtract.

15. 2. In a combined typewriting and computing machine, the combination of an adding and subtracting computing device, a movable carriage for the typewriter, a manually adjustable device to cause the computing device to add or subtract, a cam actuated by the carriage, and means actuated by the cam for shifting the manually adjustable device to restore the computing device to adding condition if during the previous operation it shall have been caused to subtract.

20. 3. In a combined writing and computing machine, the combination of an adding and subtracting totalizer, a movable carriage for the writing machine, a cam mounted in the path of the carriage and actuated thereby, means including a lever for causing the totalizer to add or subtract according to the will of the operator, and means actuated by the cam for shifting the lever to change the totalizer to adding condition if during a previous operation it shall have been caused to subtract.

25. 4. In a combined typewriting and computing machine, the combination of an adding and subtracting computing device, normally arranged for a preferred computation, a movable carriage for the typewriter, means under the control of the operator to cause the computing device to add or subtract, and means actuated by a shifting of the carriage to restore the computing device so that it may receive its preferred computation if during the preceding operation it shall have been caused to perform the operation which is not preferred.

30. 5. In a combined typewriting and computing machine, the combination of a computing device adapted to perform various computations, means for causing the computing device to normally perform a preferred computation, means under the control of the operator for causing the computing device to perform a desired computation, and means gov-

erned by the machine for causing the computing device to perform its preferred computation at the succeeding operation if during the preceding operation it shall have been caused to perform an operation which is not preferred.

70. In testimony whereof, I have hereunto subscribed my name.

GUSTAVE O. DEGENER.
